PREIONIZER

Thomas J. Carpenter and Gordon Milne, Pittsfield, Mass., assignors to General Electric Company, a corporation of New York

Application May 5, 1958, Serial No. 733,121

12 Claims. (Cl. 313—308)

This invention relates to a preionizer for an overvoltage protective device such as a lightning arrester.

One prior art form of lightning arrester comprises a stack of gap and valve units. Under lightning or other surge conditions the gap units are arced over to pass the surge to ground, and the valve units choke off the power follow current. The arc across the main electrodes of the gap unit may be magnetically elongated and driven into a plurality of soft iron or magnetic material plates as in copending Snell patent application Serial No. 547,780, which was filed on November 18, 1955, now abandoned; or it may be magnetically elongated and driven into a plurality of auxiliary electrodes by a coil as in copending Carpenter and Olsen patent application Serial No. 496,442, which was filed on March 24, 1955, now Patent No. 2,890,389. Both of these copending patent applications are assigned to the same assignee as the instant one.

It has been well known to use a preionizer for the main gap of the gap unit. The purpose of the preionizer is to help break down the main gap at low and consistent impulse levels. This is done by having the preionizer preionize the main gap. This may be done by having the preionizer emit corona or arc over at impulse and emit its photons into the main gap to illuminate or ionize its dielectric gap. However, prior art preionizers have not been entirely satisfactory. One reason is the requirement that the preionizer not emit corona at normal or rated operating voltage of the arrester. This is a requirement which has been difficult to control. Corona at normal or rated operating voltage is undesirable because it causes radio noise and may have a corrosive effect on other lightning arrester parts as well as the preionizer itself. This requirement has been difficult to control for several reasons. The allowable space in the gap unit for the preionizer is very small. Therefore, the preionizer must be very small as compared to other parts of the arrester. The preionizer may comprise a pair of electrodes which are spaced by an air gap or by a dielectric spacer. Accurate gap and dielectric spacer settings have been difficult to obtain without high cost, and even after they are obtained they are difficult to maintain. For instance, corona or arcing in the preionizer may corrode its parts which results in changed settings, or the settings can be altered by jarring of the arrester. A further disadvantage of prior art preionizers is that they cannot be reliably calibrated and tested prior to their incorporation into the gap units.

It is an object of this invention to provide an improved preionizer which will overcome the above discussed disadvantages of prior art preionizers.

In the preferred form of our invention the preionizer is an integral and generally C-shaped element. The spaced ends of the C-shaped element define the preionizer gap. The element may be made by forming a ceramic composition into a closed circular, rectangular, square, oval or other equivalent shape. Thereafter, an accurate gap can be very easily and economically obtained in the formed shape by cutting the gap in one of its sides. The cut ends of the C-shaped element which define the gap are

integral with the main body of the C-shaped element. Therefore, the original gap setting will be self-maintained.

The invention is not restricted to a C-shaped element. Integral members having other configurations can be used. For instance, a member could have an H-shaped slot formed in it in which the spaced integral projections in the H-shaped slot define the preionizer gap. If the slot were U-shaped then the end surface of the integral projection in the U-shaped slot and the adjacent surface 10 of the member would define the preionizer gap. The member could also be triangular with a triangular slot and one corner of the member could be slotted to define the gap. Another configuration is a P-shaped element which is gapped at the lower left hand corner of the loop of 15 the P-shape. Therefore, broadly the invention comprises a preionizer which is essentially a single integral member which has two spaced surfaces or projections or a spaced surface and projection which together define a gap.

The features of our invention which we believe to be 20 novel are set forth with particularity in the appended claims. Our invention itself, however, both as to its organization and method of operation, together with further objects and advantages thereof, may best be understood by reference to the following description taken in connection with the accompanying drawing, in which:

Figure 1 is a partly broken away top view of a lightning arrester gap unit having one form of the invention incorporated therein; and

Figure 2 is a front elevation view of the gap unit of 30 Figure 1; and

Figure 3 is an enlarged perspective view of the preionizer element and its support means.

In the drawing is illustrated a magnetic plate gap unit 35 of the type claimed in the previously mentioned copending Snell patent application. However, the invention is also useful in a gap unit of the type claimed in the previously mentioned copending Carpenter and Olsen patent application. The latter gap unit uses elongated auxiliary electrodes and a magnet coil to move the arc.

The magnetic plate gap unit comprises a plurality of 40 unitary magnetic and non-magnetic material plates 1, 2. They are stacked with respect to each other in spaced relationship between two spaced electrical insulating material support members 3. The parts 1 of the plates are the magnetic material portions, and the parts 2 are the non-magnetic material portions. The parts 1 can be made from soft iron. The parts 1 and 2 are inserted with respect to each other and may be connected to each other by welds.

Top and bottom plates 4 are bolted to the spaced plate 45 supporting members 3. The plates 4 support a pair of spaced electrodes 5. The spaced ends of electrodes 5 define a main gap 6 of the magnetic plate gap unit.

When an overvoltage occurs across the electrodes 5 the gap 6 will arc over. The arc is illustrated by reference number 7. A magnetic field will be created in the magnetic parts 1 as illustrated by the lines 8 when the direction of arc current is from top to bottom as indicated by its plus sign. When the arc current is reversed so will the magnetic field 8. This magnetic field will react with the magnetic field of the arc 7 to move the same into the plates 1, 2.

The parts 1 have blind aligned slots 10 formed therein and the electrodes 5 are disposed in these slots. The magnetic movement of the arc 7 is in the direction of arrow 9 into the blind end of the slots 10. When the arc 7 reaches the plates it divides into a plurality of smaller series arcs. The parts 2 prevent the series arcs from being driven to the outer edge of plates 1, 2 where they could recombine into a long continuous arc.

The preionizer 11 is located adjacent to the open ends of the slots 10. It is connected electrically in parallel.

with the electrodes 5. This electrical connection and the support for the preionizer 10 may comprise a pair of metallic and resilient conducting strips 12 which are connected as by welding to the insides of plates 4. The free ends of strips 12 may have slots 13 formed therein which are intended to have the end tabs 14 of the preionizer 11 snapped therein. The opposite ends of the preionizer 11 adjacent to tabs 14 may be silver plated or the like to obtain good electrical contact between preionizer 11 and strips 12.

The preionizer 11 is generally C-shaped and its spaced ends 15 define a preionizer gap 16 for preionizing the main gap 6. The preionizer 11 is positioned to have its slotted side or gap 16 face toward the main gap 6. If the preionizer were turned around about 90 degrees about its lengthwise axis the line of sight through the gaps 16 and 6 would be free and clear of any obstructions and by the term facing each other or one gap facing the other or similar expressions is meant an arrangement in which the line of sight through the two gaps is free and clear of any obstructions.

When the gap unit is subjected to an overvoltage such as a lighting impulse the gap 16 will break down and ionize the gas space in the gap 6 which will then arc over. Of course, it will be appreciated that this sequence of events occurs practically instantaneously.

In one commercial form of the invention the gap unit was rated at 3 kv.; the preionizer was about 1" long, $\frac{1}{2}$ " wide and $\frac{1}{8}$ " thick; and the gap 16 was about $\frac{30}{1000}$ " long and the gap 6 was about $\frac{80}{1000}$ " long. However, the invention is not limited to these dimensions. Rather, they are given to illustrate one practical working embodiment of the invention.

The preionizer was made from fired barium titanate although other ceramic compositions have been used. The preionizer withstood 10 kv. R.M.S. at 60 cycles without flashing over and there was no corona at the ends 15 below the 3 kv. operating rating of the gap unit.

The uncut side of the preionizer is the electrical equivalent of capacitance between strips 12 and their respective electrodes 5. The cut side of the preionizer also provides capacity. Therefore, the gap 16 is capacitively in shunt with the first mentioned capacitance and the main gap electrodes 5. While the preionizer gap 16 could be resistance coupled, capacity coupling is desirable for when gap 16 is arced over, the gap current increases as frequency increases and more effective preionization of main gap 6 results. The gap spacing 16 can be accurately controlled dimensionally which results in accurate control of the breakdown voltage of gap 16. After breakdown of the gap 16 the current as a function of voltage and frequency can be controlled by the dimensions and by the composition of the material of the preionizer.

A further improvement which we have found to be useful is to coat the ends 15 with graphite. When the ends 15 are coated with graphite the consistency of the spark over level is better than when uncoated. Although graphite is more effective the invention is not restricted to this particular material since other coatings such as lead and metallic oxides can also be used to obtain low and consistent sparkover voltages.

In many prior art preionizers the photons for illuminating the main gap are produced by a corona discharge by overstressing the dielectric about a metal electrode that contacts a solid electrical insulating material plate, spacer, pad or the like. In these devices the corona starting level as a function of the applied voltage is difficult to control and therefore the level of current in the device must be very low. The lack of control over the corona starting level may cause radio noise below the rated voltage of the arrester and promote corrosion of the arrester elements. Also, the effectiveness of the ionization is reduced due to the severe limitation on the current through the device.

In the invention the voltage level at which the preionizing discharge occurs can be accurately controlled by the gap spacing. In actual practice this voltage is between about 110 to 125 percent of the rated voltage of the gap unit. Consequently, there is no corona below the rating of the gap unit. Therefore, radio noise and corrosion is eliminated. Also, because the voltage level at which the preionizing device becomes effective is above the rated voltage of the gap unit the impedance of the capacity coupling of the cut sides of device can be decreased by changing the dielectric constant or shape of the ceramic body. By decreasing the impedance more effective ionization is obtained due to the higher current discharge through the gap of the device.

A further advantage of the device is that since it is essentially an integral single piece element it has dimensions or a setting which will not be affected by handling, assembly, shipment or storage. It also can be tested before assembly into a lightning arrester gap unit. These advantages are not true of prior art preionizers which are assembled from a plurality of parts since variations in these parts or their relative spacing during or after assembly may affect the performance of the preionizer.

While there has been shown and described a particular embodiment of the invention, it will be obvious to those skilled in the art that changes and modifications may be made without departing from the invention, and, therefore, it is intended by the appended claims to cover all such changes and modifications as fall within the true spirit and scope of the invention.

What we claim as new and desire to secure by Letters Patent of the United States is:

1. In an overvoltage protective device which has a pair of spaced electrodes, a preionizer for the gap of said electrodes, said preionizer being connected electrically in shunt with said electrodes, said preionizer comprising an integrally formed element which has two surfaces which together define a gap which is disposed adjacent to and facing the gap of said electrodes.

2. In an overvoltage protective device which has a pair of spaced electrodes, a preionizer for the gap of said electrodes, said preionizer being connected electrically in shunt with said electrodes, said preionizer comprising an integrally formed element which has two projections which together define a gap which is disposed adjacent to and facing the gap of said electrodes.

3. In an overvoltage protective device which has a pair of spaced electrodes, a preionizer for the gap of said electrodes, said preionizer being connected electrically in shunt with said electrodes, said preionizer comprising an integrally formed element which has a projection and surface which together define a gap which is disposed adjacent to and facing the gap of said electrodes.

4. In an overvoltage protective device which has a pair of spaced electrodes, a preionizer for the gap of said electrodes, said preionizer being connected electrically in shunt with said electrodes, said preionizer comprising an integral generally C-shaped element which has its spaced ends disposed adjacent to and facing said gap.

5. In an overvoltage protective device which has a pair of spaced electrodes, a device for controlling the impulse breakdown of the gap of said electrodes to a low and consistent level without producing corona below the normal rated voltage of said gap, said device being connected electrically in shunt with said electrodes and comprising an integral generally C-shaped impedance element whose spaced ends are disposed adjacent to and facing said gap.

6. In an overvoltage protective device which has a pair of spaced electrodes, a preionizer for the gap of said electrodes, said preionizer being connected electrically in shunt with said electrodes, said preionizer consisting essentially of an integral generally C-shaped impedance element whose spaced ends are disposed adjacent to and facing said gap, said spaced ends being spaced from each

other by a gap whose length is small with respect to the length of said element and the length of the gap of said electrodes.

7. In an overvoltage protective device which has a pair of spaced electrodes, a device for controlling the impulse breakdown of the gap of said electrodes to a low and consistent level without producing corona below the normal rated voltage of said gap, said device being connected electrically in shunt with said electrodes and consisting essentially of an integral generally C-shaped ceramic element whose spaced ends are disposed adjacent to and facing said gap, said spaced ends being spaced from each other by an air gap whose length is short relative to the length of said element and the length of the gap of said electrodes, and said spaced ends being coated with graphite.

8. In a lightning arrester which has a pair of electrodes which are spaced from each other by an air gap, a preionizer for said air gap consisting essentially of an integral generally C-shaped high dielectric ceramic element whose ends are spaced from each other by an air gap which is disposed adjacent to and faces said first mentioned air gap, said element being connected electrically in parallel with said first mentioned air gap, said preionizer air gap having a length which is short relative to the length of said element and said first mentioned air

10

gap, and said preionizer gap ends being coated with graphite.

9. A preionizer which consists essentially of an integrally formed impedance element which has two surfaces which are positioned opposite to each other in spaced relationship to define a gap therebetween.

10. A preionizer which consists essentially of an integrally formed impedance element which has two projections which are positioned opposite to each other in spaced relationship to define a gap therebetween.

11. A preionizer which consists essentially of an integral generally C-shaped impedance element whose ends are spaced from each other by a distance which is short with respect to the length of said element.

12. A preionizer which consists essentially of an integral generally C-shaped high dielectric constant ceramic element whose ends are spaced from each other by a distance which is short with respect to the length of said element and whose ends are coated with graphite.
